UNITED STATES PATENT OFFICE.

NILS J. LINDSTROM, OF EVANSVILLE, MINNESOTA.

BAND-CUTTER AND FEEDER.

SPECIFICATION forming part of Letters Patent No. 549,142, dated November 5, 1895.

Application filed January 28, 1895. Serial No. 536,461. (No model.)

To all whom it may concern:

Be it known that I, NILS J. LINDSTROM, a citizen of the United States, residing at Evansville, in the county of Douglas and State of Minnesota, have invented certain new and useful Improvements in Band-Cutters and Feeders; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in band-cutters and feeders for thrashing-machines.

The objects of my invention are, first, to provide a band-cutter and feeder which may readily be applied to any ordinary thrasher; second, to provide a band-cutter and feeder which will cut all the bands and thoroughly spread the grain before it reaches the cylinder. These and other objects I attain by the 25 novel construction and arrangement of parts illustrated in the accompanying drawings, in which—

Figure 1 is a side elevation of the front portion of a thrashing-machine with my complete band-cutter and feeder attached thereto.

30 Fig. 2 is a plan view of Fig. 1. Fig. 3 is a sectional side view substantially as on the line *a a* in Fig. 2. Fig. 4 is a plan view of the lower feeder-bars. Fig. 5 is a left-hand

35 end view of Fig. 4. Fig. 6 is a detail view of one of the band-cutter knives. Fig. 7 is an enlarged end view of the knife-cylinder, which by its knives cut the bands. In this view only one knife is shown. Fig. 8 is a

40 right-hand side view of Fig. 7 with the knife in section as on the line *b b* in Fig. 7. Fig. 9 is a detail side view of a portion of Fig. 1.

Referring to the drawings by reference-numerals, 10 is the cylinder of the thrashing-machine.

45 11 is the cavity or house, in which the cylinder works and does the thrashing proper.

12 is the cap or lid covering the cylinder-house.

50 13 are the two usual side arms projecting out from the machine and between which in common thrashers is secured a table, (not

shown,) upon which the grain is spread by hand or otherwise and fed toward the cylinder.

55

14 are braces supporting the arms 13.

Of the old and well-known parts thus described I remove only the old-style feeding-table, and insert in its place and secure to the arms 13 my band-cutter and feeder, which 60 will now be described, and which comprises a feeder-frame, consisting of the two side boards 15, having their upper edges enlarged by the frame-bars 16, and the two transverse bars 17 and 18, which have their ends secured 65 by lag-screws 19 to the side-boards 15, and a carrier-frame, consisting of the side-boards 20 and the carrier-supporting table 21, which secures the side-boards 20 together, and mechanisms mounted in said frames, as will 70 presently be fully described. The side-boards 20 of the carrier-frame are rigidly secured with their rear ends, as at 22, to the side boards 15 of the feeder-frame, so that the one frame forms an extension of the other. The 75 carrier-frame 20 21 is intersected at 23 and provided with the hinges 24, so that the front portion of the carrier-frame may in transportation of the machine be folded in under the feeder-frame and secured by the hook 25, 80 as shown in dotted lines in Fig. 1.

26 are detachable sticks for supporting the carrier-frame by their shoulders 27, upon which rest the stick-pockets 28, secured upon the side-boards 20 and housing the upper end 85 of the sticks.

Upon the arms 13 I secure at 29 the goose-neck-shaped keepers 30, under which are retained by the pins 31 the stud 32 of the metallic plates 33, which are secured upon the 90 side-boards 15. By these means the feeder-frame is held in its proper proximity to the cylinder. Said frame is further supported by the trunnions 34, projecting from the castings 35, secured upon the side-boards 15 at a 95 point calculated to balance the frame. The trunnions 34 are capable of both rocking and sliding under the elongated keepers 36, secured upon the arms 13. By this arrangement

when the operator wishes to get access to the lower part of the inclosure of the cylinder, which is often desirable, all he has to do is to remove the pins 31 and sticks 26, slide the feeder-frame forward as far as the trunnions 100

34 will move in the slots in the keepers 36, and then tilt the frame on the trunnions up with its rear end, as shown in dotted lines 37 in Fig. 1, or as much more up as may be necessary. In the front and rear ends of the carrier-frame 20 21 are journaled, respectively, the rollers 38 and 39, over which is stretched the endless carrier-apron 40, provided with the cross-bars 41, and supported as to its upper part by the table 21. The shaft 42 of the roller 39, which operates the apron, projects beyond the framework and is provided with a rigidly-secured sprocket-wheel 43, which, driven by the belt chain 44, drives the roller 15 and apron.

45 is a pulley secured upon the one end of the cylinder-shaft 46 for driving the cylinder. Upon the other end of the cylinder-shaft is secured a small pulley 47, which by means 20 of the belt 48 drives a larger pulley 49, secured upon the end 50 of the shaft 51, which is journaled in the bearings 52, secured upon the front corners of the feeder-frame. (See Fig. 2.) Upon the shaft 51 is secured the 25 knife-cylinder, which consists of a four-cornered block or roller 53, having upon each of its four sides, secured by screws, as 54, a metallic plate or strip 55, of which one edge overhangs the angular corner of the cylinder 30 and is provided with teeth, as 56, (best shown in Figs. 7 and 8,) which tends to spread and separate the grain while the bands of the bundles are cut by the knives 57, which are of the shape shown in Fig. 6, having the cutting-edge 58, the toe 59, the shoulder 60, and the hole 61. These knives are secured in such alternate rows upon the four flat sides of the block 53 that the circles in which all the knives move are about equal distances 35 apart and close enough together to allow no band of a bundle to pass uncut.

In order to facilitate the removal of the knives from the roller for sharpening or repair, each knife is secured upon the roller by 40 a small socket, as 62, which is secured by the screws 63 upon the roller and provided with a central slot 64, in which the knife is inserted between the lips 65, through which and through the hole 61 in the knife is inserted 45 a spring-pin 66, by which the knife is detachably retained in the socket.

It will be observed that the socket is first secured to the roller, and the knife is then inserted with its toe 59 into the cavity 67 at 50 one end of the slot in the socket and with its shoulder 60 bearing against the outer face of the socket near the opposite end of the slot, and the spring-pin is then inserted.

Turning now to a consideration of the feeding mechanism, which spreads and delivers the grain to the cylinder, 68 are the lower feeder-bars, which in the present instance are four in number. These bars work so close by each other and have their side edges provided with the upwardly-projecting guards 69 that no grain can pass down between them, even when the bars proper vibrate above and

below each other. The said guards 69 also help greatly to spread and even out the grain, as do also the fingers 70, which project out 70 from the rear end of each of said feeder-bars. The upper side of the feeder-bars, as well as their fingers 70, are provided with corrugations or teeth 71, slanting toward the cylinder of the thrasher. The feeder-bars are 75 provided near their middle with arms, as 72, which engage a multiple-crank shaft 73, (best shown in Fig. 5,) journaled in the bracket 74, secured below and directly to the right-hand side-board 15 of the feeder-frame, and in the 80 journal-box 75, secured upon the brace 76, which is secured at 77 to the left-hand side-board 15 and with its lower end to a bracket 78, (see Figs. 1 and 9,) of which the lower end is provided with a slot 79, in which is adjustably secured the stud 80, carrying the chain-stretcher pulley 81. The bracket 78 is further steadied by the brace 82, and has its upper end secured to the side board 15 by the screws 83, between which it is provided with the hole 84, which serves as a journal-bearing for the 85 shaft 42 of the roller operating the endless carrier-apron. The sprocket-wheel 85, driven by the chain 44 and rigidly secured upon the end of the multiple-crank shaft 73, revolves 90 the latter. The rear ends of the feeder-bars 68 are held in a suitable elevation in front of the cylinder by supporting links or rods 86, (see Fig. 3,) pivotally connected, with their 95 upper ends to the feeder-bars, as at 89, and with their lower ends to the cross-frame bar 18, as at 90, so that the entire feeder-bars are free to both reciprocate and vibrate when the crank-shaft revolves, the front ends of the feeder-bars, however, having the greatest 100 vibration.

From the upper cross frame-bar 17 are suspended by similar pivoted rods 91 the upper feeder-bars 92, which near their middle are provided with the arms 93, engaging the multiple-crank shaft 94, which is journaled in the bearings 95, secured upon the top of the feeder-frame, and has upon one of its ends rigidly secured a sprocket-wheel, as 96, driven by the chain 44, which is an endless-belt chain driven by the small sprocket-wheel, 97, secured on the shaft 50, and drives the 105 wheels 43, 85, and 96, to which it is stretched or adjusted by the stretcher-pulley 81.

Each one of the upper feeder-bars 92 is 110 made up of two parallel bars secured together a suitable distance apart by the cross-bars 98, to which is secured the arm 93, engaging the crank-shaft. The upper feeder-bars 92 are provided at their bottom side with corrugations or teeth 99, slanting toward the cylinder. 115

It will be observed that the corrugated surfaces of the upper and lower feeder-bars bulge toward each other, so as to always leave sufficient opening between the front ends of the 120 upper and lower bars for the grain to enter continually from the carrier-apron.

It will also be observed that the upper crank-shaft is of a greater stroke than the

lower one, so that although the two shafts revolve at the same speed the upper feeder-bars have a greater motion than the lower ones, and thus, in conjunction with the latter, do not only feed the grain along, but also spread it by the unequal motion of the feeders.

In operation the cylinder when driven, as usually, drives the entire mechanism of my band-cutter and feeder by means of the pulley 47, belt 48, belt chain 44, and sprocket-wheels, as described. The bundles of grain are thrown upon the endless apron 40, which carries them heads foremost in under the knife-cylinder, where the bands are cut by the knives 57, and the bundles partly spread by the teeth 56 of the plates 55. The feeder-bars then move the grain toward the cylinder, while they also thoroughly spread it by their unequal reciprocation and by the vibration 20 of the guard-plates 69.

How my device is attached to the thrasher by the keepers 30 and 36 has already been described.

I am aware that prior to my invention band-cutters and feeders have been constructed with a knife-cylinder and with corrugated reciprocating feeder-bars, so I do not claim these elements, broadly; but

What I claim, and wish to secure by Letters Patent, is—

1. In a band-cutter and feeder, the combination with the frame bars or arms 13, of the thrasher of the open-ended keepers 30, and the slotted keepers 36, secured thereon, a feeder frame adapted to be placed between said arms 13, and having provided upon its opposite sides the trunnions 34, adapted to rock and slide in the keepers 36, and with the pegs 32, passing in under the open-ended 40 keepers and the pins 31, for retaining the pegs and the frame in place, substantially as and for the purpose set forth.

2. In a band-cutter and feeder, the combination with the arms 13 of the frame of the thrasher of a feeder frame, entering in between and being provided with trunnions and pegs, and supported by said arms, and having a sliding and tilting motion thereon by which the feeder frame may be moved partly away from the cylinder and tilted upward 50 with the end nearest the thrasher so as to gain access to the lower part of the cylinder house, substantially as set forth.

3. A band-cutter and feeder having a knife cylinder consisting of an elongated four-cornered block, provided upon its four corners with toothed plates adapted to move and spread the grain and upon its flat sides with knives for cutting the bands of the bundles, and means for driving said knife-cylinder and 60 means for carrying the bundles in under the knife-cylinder, substantially as shown and described.

4. A band-cutter and feeder having mounted in a suitable frame an upper and a lower 65 set of vibrating and reciprocating feeder-bars bulging with their corrugated surfaces the one set toward the other, the one set of feeder-bars having greater motion than the other, so as to spread the grain while feeding it, the 70 lower set of bars having secured upon its sides the upwardly projecting grain-guarding and spreading side plates 69, and work close by each other, two multiple crank shafts of different strokes for operating said feeder-bars, substantially as and for the purpose set forth.

In testimony whereof I affix my signature in presence of two witnesses.

NILS J. LINDSTROM.
